UNITED STATES PATENT OFFICE.

JOHN W. PEELLE, OF BROOKLYN, NEW YORK, ASSIGNOR TO THE PEELLE COMPANY, OF NEW YORK, N. Y., A CORPORATION OF NEW YORK.

CONTROLLING MEANS FOR ELEVATOR-DOORS.

1,257,109.

Specification of Letters Patent. Patented Feb. 19, 1918.

Application filed April 8, 1916. Serial No. 89,878.

To all whom it may concern:

Be it known that I, JOHN W. PEELLE, a citizen of the United States, residing at the borough of Brooklyn, in the city of New York, county of Kings, and State of New York, have invented certain new and useful Improvements in Controlling Means for Elevator-Doors, of which the following is a specification, reference being had therein to the accompanying drawings, which form a part thereof.

My invention relates to controlling means for elevator doors and more particularly to a motor actuated mechanism common to, and operative in relation to, all of the doors in an elevator shaft.

A controlling means for elevator doors made in accordance with my invention is especially adapted for use in connection with vertically sliding elevator doors, which ordinarily are made in a plurality of sections so connected as to have simultaneous movement in opposite directions. In those doors of this type which are commonly known as "semi-automatic," one of the door sections is of relatively greater weight than the other, so as to secure an overbalancing of the sections in a manner to cause the doors to either automatically open, or automatically close, according to which section is overweighted. In this type of doors, it is necessary to provide a limit stop to prevent the opening or closing of the doors except under the control of the elevator operator. Heretofore in semi-automatic elevator doors where the opening or closing of the doors is under the control of a motor, it has been necessary to provide each door with its own motor, thus complicating the elevator installation and making it prohibitive to use this mechanism in connection with inexpensive installations such as are commonly used in factories and warehouses. To obviate this condition, I provide a controlling mechanism which is common to all doors in an elevator shaft but may be used in connection with any one of said doors, without having any operative effect upon the other doors, said mechanism being controlled from the car and its operative effect being determined by the position of the car in the elevator shaft. In the embodiment of my invention shown in the accompanying draw-

ings, I have illustrated it as applied to self opening doors, the mechanism being so constructed that while the position of the car will control the opening of the door to the extent that no door can be opened unless a car is on a substantial level with the sill of the doorway closed by the door to be opened, the motor for imparting movement to the door will act as a check or retard in controlling the movement of the door section upon which it operates when the same has movement, the draft mechanism actuated by the motor being so associated with the several doors that it will be normally in the operative relation to each of said doors but will pass from this relation upon the actuation of any door.

In addition to its functions in opening and closing the several elevator doors, the motor and its draft mechanism may be utilized as a supplemental lock for preventing the opening of any door while the elevator car is in travel, or when it is not at the door to be opened.

The invention consists primarily in such novel features of construction and combination of parts as are hereinafter set forth and described and more particularly pointed out in the claims hereto appended.

Referring to the drawings:—

Figure 1 is a front elevation of two of a series of elevator doors showing my controlling means therefor:

Fig. 2 is a side view of the adjacent body portion of two doors in the closed position; and

Fig. 3 is a detailed view showing the limit stop mechanism and the controlling means therefor.

Like letters refer to like parts throughout the several views.

In the accompanying drawings, I have illustrated my invention in connection with the elevator doors upon the two adjoining floors of a building, it being understood that by a mere extension of the draft cables and their appurtenances, the controlling means may be applied to any desired number of doors in a shaft. In the drawings, I have also illustrated the invention in connection with semi-automatic doors of the self-opening type, in connection with which the form of the invention shown is especially adapted.

In the drawings, the elevator shaft itself is illustrated at *a*, said shaft having at opposite sides thereof parallel guide rails *b* for the elevator doors. Each of the doors shown 5 comprises two sections, an upper section *c* and a lower section *d* these sections being caused to move simultaneously and to the same extent in opposite directions by the flexible connections *e* passing over the 10 pulleys or sheaves *f*. The lower section *d* in the form of the invention shown, is heavier than the upper section *c* so as to cause the door to have a normal tendency to open. This overbalancing of the upper door section by the lower section may be secured by 15 making the lower section of heavier construction, or by merely applying thereto an overbalancing weight *j*.

The section *d* in the form of the invention 20 shown is provided with a flanged top rail or truck bar *g* adapted to span the gap between the sill and the elevator door for the purpose of facilitating the loading and unloading of the car. This top rail or bar is 25 extended laterally from the section *d* as at *h*, said extensions having the two-fold function of a connection for the shackles of the flexible cables *e* and of a support for an angular bracket *i* by means of which power 30 may be applied to the doors for closing same.

In semi-automatic doors, it is essential to provide restraining means counteracting the normal tendency of the doors to move under gravity, such means being in the nature 35 of a limit stop which must be released to permit the opening or closing of the doors. In the form of the invention shown, this limit stop comprises a latch bar *k* pivoted at *k'*, the head of said bar being normally projected beneath the top rail or bar *g* of the section *d*. Acting upon the lower arm of the bar *k* is a lever *m*, upon one arm of which the spring *n* acts in a manner to normally project the head of the bar *k* in 40 the path of the top rail or bar *g*. Carried by the lever *m* is a plunger *o* normally projecting in the path of a cam *p* carried by and movable with the elevator car *q*. By providing actuating means for the limit 45 stop of the character shown in the accompanying drawings, and means carried by the car cooperating therewith to release said limit stop when the car is on a substantial level with the sill of the door to be opened, 50 only one door of all those in a shaft may be opened at a time and that door will be the one at which the car is located at the time. Other, and manually operative, means for locking door sections together may be employed if desired, however.

Also acting upon the door sections at each doorway in the shaft, is a motor actuated controlling mechanism normally in the operative relation to all doors in a shaft to

prevent the opening of any of said doors. 65 By this construction it will be observed that each door is normally held closed by two independent mechanisms which must be successively operated to cause the opening of any door and that the operation of either 70 of these mechanisms alone will not permit the opening of the door. It will also be observed that the operation of one of these mechanisms is entirely automatic under the control of the elevator car, so that there must 75 be such a definite sequence in the operations of the controlling or locking mechanisms as will insure the presence of the car at the door which is opened.

In the form of the invention shown, I 80 provide in the upper part of the elevator shaft upon opposite sides thereof, pulleys or sheaves *r-r'* over which pass draft cables *s-s'* which also pass through openings in the brackets *i* carried by the several door 85 sections *d*. Each of said draft cables has thereon adjacent each bracket *i* and normally in engagement therewith respectively, a plurality of blocks or balls *t-t'* firmly secured to said cables. The depending ends 90 of the cables *s-s'* have attached thereto weights *u-u'* and the other ends thereof are connected to the piston of a compressed air motor *v*, or to any other desired form of motor. The motor *v* shown in the drawings is of an old and well-known type and a detail description thereof will not be entered into. The motor is controlled by means of an old and well known form of magnetic valve *w* in circuit with the circuit 100 controlling push buttons *w'* and *w²* carried by the elevator car *q*.

The operation of the herein described controlling mechanism is substantially as follows:—

When a car is between floors, the limit stop mechanism of all of the doors in the shaft, will be so set as to have the latch bar *k* projected in a manner to cause the upper end thereof to be in the path of the top rail 110 of bar *g* of its door and all of the blocks or balls *t-t'* upon both sides of the several doors will be in operative engagement with the under side of their co-operating brackets *i*. As the car passes each floor, in the form 115 of the invention shown, the cam *p* thereof will engage the plunger *o*, and through the lever *m* oscillate the bar *k* in a manner to disengage it from the top bar *g*. By reason of the fact that the section *d* is overweighted 120 the release of the bar *k* would permit the automatic opening of the door, if the motor *v*, through the cables *s-s'* and the balls *t-t'* thereon, did not prevent movement of the doors. As the car passes each floor the 125 stop *k* will return to its normal projected position beneath the top bar *g*.

If it be desired to open any door, the car

is brought to rest at the sill thus holding the stop k in the retracted position. The button w' is then pushed to cause the actuation of the valve w in a manner to admit 5 air below the piston of the motor v , thus feeding out the cables $s-s'$ in a manner to cause the several blocks or balls $t-t'$ to recede from the brackets i . This movement of the cables $s-s'$ will permit the door section 10 d to descend, the rate of this descent being controlled by the rate of movement of the cables $s-s'$.

It will be observed, however, that while the door at the doorway where the elevator 15 is stopped is permitted to open the remaining doors will be held closed solely by their limit stops k since the blocks $t-t'$ operative upon said other doors will recede from the angles i .

20 When it is desired to close the door, the operator merely pushes the button w^2 which will actuate the valve w in a manner to reverse the motor v and raise all of the blocks or balls $t-t'$, and thus raise any door which 25 may happen to be open at the time, said blocks or balls coming to rest directly beneath all of the angles i of the several doors preparatory to the next actuation of any of said doors. The mechanical closing of the 30 doors under the control of the operator avoids any necessity for any nice proportioning of the relative weights of the different sections of the doors when a plurality of sections are used. If it be desired to 35 fully close the doors before starting the car, the blocks or balls $t-t'$ will hold the doors in the closed position until the car has been started, and the limit stop k becomes operative in relation to the door which has just 40 been closed.

It is not my intention to limit the invention to the precise details of construction shown in the accompanying drawings, it being apparent that such may be varied 45 without departing from the spirit and scope of the invention.

Having described the invention, what I claim as new and desire to have protected by Letters Patent is:—

50 1. A controlling mechanism for elevator doors which doors consist of two sections operatively connected, whereby they will have simultaneous vertical movement in opposite directions, and the upper of said sections being overbalanced by the lower, said mechanism consisting of a stop operative upon the lower door section of each door in a shaft when it is in the closed position, actuating means for each of said stops, 55 mounted in said shaft, means carried by an elevator car coöperating with said actuating means whereby said stop can be released only when the car is at a door opening, a motor, a plurality of cables operatively con-

nected with said motor and extending vertically in the shaft upon opposite sides of each door in said shaft, a plurality of blocks carried by each of said cables, a block upon each cable being adjacent the lower section of each door in the shaft, brackets carried 65 by the lower section of each door, said cables passing freely through said brackets and said blocks normally engaging the under side of said brackets respectively, and means carried by the car whereby said motor may 70 be actuated to lower said blocks to permit the opening of any door in the shaft when the stop mechanism therefor is released by the car, or to raise said blocks, to close any door which is opened.

2. The combination of a plurality of elevator doors which comprise two vertically sliding sections movable in opposite directions, the lower of which overbalances the upper, of a plurality of stops operative upon 85 the lower sections of said doors respectively when they are in the closed position, actuating means for said stops mounted adjacent each door, means carried by an elevator car coöperating with said actuating means re- 90 spectively, a motor, cables operatively connected with said motor and extending upon opposite sides of each door, manually operative controlling means for said motor carried by the elevator car and operative inde- 95 pendently of the movement of the car; and coöperating means carried by said cables respectively and the lower section of each of said doors whereby said cables may have movement independently of said door sec- 100 tion or may have movement with any door section the stop for which has been released, when said motor has movement in one direction, and any opened doors will be closed when said motor has movement in the oppo- 105 site direction.

3. A controlling mechanism for elevator doors comprising two sections operatively connected whereby they will have simultaneous movement in opposite directions, the upper of said sections being overbalanced by the lower, embodying therein a top bar upon the lower section, lateral extensions upon the said top bar, a limit stop adapted to pass under one of said extensions when the 110 door is closed, actuating means for said limit stop, means carried by an elevator car coöperating with said actuating means, an angle bracket having an opening there- 115 through carried by the lower section of each door in a shaft, a motor, cables connected with said motor, pulleys at the top of the shaft about which said cables pass, said cables passing through the openings in the brackets on each of the door sections re- 120 spectively, blocks secured to said cables below said brackets whereby any door section may have downward movement with 125

said cables and said blocks will recede from the door sections remaining in closed position, so that the several doors of the shaft may be selectively opened as determined by the position of the elevator car and controlling means for said motor.

In witness whereof I have hereunto affixed

my signature in the presence of two subscribing witnesses, this 4th day of April, 1916.

JOHN W. PEELLE.
